UNITED STATES PATENT OFFICE.

CLEMENT V. WHALLON, OF NAMPA, IDAHO.

REPAIR LID OR CAP.

1,284,514.

Specification of Letters Patent. Patented Nov. 12, 1918.

Application filed July 24, 1918. Serial No. 246,527.

To all whom it may concern:

Be it known that I, CLEMENT V. WHALLON, a citizen of the United States, residing at Nampa, in the county of Canyon and 5 State of Idaho, have invented certain new and useful Improvements in Repair Lids or Caps, of which the following is a specification, reference being had to the accompanying drawings.

10 This invention relates to closures, lids or stoppers, and particularly to a cap or lid designed for the purpose of closing water and gas meter boxes and the shut-off boxes of water, gas and sewer pipes, though not necessarily limited to uses of this character.

15 The general object of an invention of this character is to provide a cap or lid of a very simple construction and which is very easily attached to or detached from the 20 body to which the lid or cap is applied.

A further object is to provide a means for locking a lid, cap or stopper in place against removal from a body to which it is applied, including a bolt or screw and a member 25 which, as the bolt or screw is rotated, has an increasingly wedging engagement with the body.

A further object is to provide a lid having means carried entirely on the lid whereby 30 it may be engaged with and locked upon a body.

A still further object is to provide a lid or stopper adapted to be applied to annular or other bodies to close the same, the lid 35 being provided with an integral lug having a beveled face and with a locking bolt passing through the lid and having a nut which, when the bolt is turned in one direction is forced into wedging engagement with the 40 inclined face of the wall of the body to thereby lock the lid or stopper upon the body.

Figure 1 is a diametrical section through a tubular body and a cap or lid for the 45 same constructed in accordance with my invention; and

Fig. 2 is a plan view of the construction shown in Fig. 1.

Referring to the drawings, it will be seen 50 that my improved lid or stopper comprises a circular cap designated 10, preferably formed of cast iron or other suitable material of like character and formed with a downwardly projecting lug 11 extending 55 diametrically across the under face of the cap. This lug at one end is formed with

a beveled face 12 and preferably the lug at its end opposite the beveled face and at its junction with the inner face of the cap 10 is formed with a notch 13. The lug 11 does 60 not extend entirely across the under face of the lid, but the lid is formed with a bolt hole through which a bolt 14 extends. The head 15 of this bolt is preferably many-sided and is usually, though not necessarily, 65 contained in a countersunk recess 16 in the outer face of the cap 10. The bolt 14 at its lower end is screw-threaded as usual and carries a nut 17 and is upset at 14^a to prevent the removal of the nut 17. 70

In the use of this invention, the cap is applied over the body 18 in the manner illustrated with the lug 11 inserted within the body and the nut 17 at the lower end of the bolt. The passage through the lid for 75 the bolt expands downward so that the bolt has a slight play. Now the lid is inserted and then the bolt is turned by means of the many-sided head. The nut is held from rotation between the side wall of the body and 80 the extreme lower corner of the lug and, as a consequence, the nut cannot turn though it can shift. By now rotating the head of the bolt, the nut is drawn upward into wedging engagement between the inclined face 85 of the lug and the wall of the casing or body to which the lid is applied. By rotating the bolt in the opposite direction, the nut 17 will be gradually worked down until 90 it is released from its wedging engagement so that the cap may be removed.

This lid, cap or stopper, though primarily designed for repair purposes, can also be used for closing a pipe, box, or other receptacle in the first instance. It is particularly 95 designed and peculiarly adapted for use as a cover or lid for water and gas meter boxes and for the shut-off boxes of water, gas and sewer pipes. The same principle, however, can be used for the lids or covers of manholes or for any box, pipe, or casing. The size of the lid will, of course, depend upon the size of the box and the thickness of the lid and the size of the locking devices will also, of course, depend upon the size of the 100 body to which it was to be applied and the strain which would be liable to come upon this body. The notch 13 is provided in the lug 11 for the purpose of giving room for the slight flange or fin caused on the inside 110 of the pipes by the cutting of the pipes in repair work. This notch 13 fits over this

fin if the fin is present, and gives the lug a firm contact over its end surface with the pipe or body in cases where old pipe has been cut and this device is used thereon, 5 while at the same time this notch will not affect the contact of the lug where the new pipe or casing is used. I wish it particularly understood that I do not limit my device to its use as a means for closing pipes 10 or the boxes or casings of water or gas meter boxes, etc., as the principle of the device may be used in a large number of circumstances to secure the closing of a body and the locking of the closure thereto.

15 I claim:—

1. A self locking lid or stopper comprising a cap having a lug extending from its inside face and disposed diametrically to the cap, one end of the lug being inclined, a bolt 20 passing downward through the cap opposite said inclined face, and a nut engaging said bolt and engageable with the inclined face of the lug.
2. A self locking lid including a cap having a downwardly extending diametrically disposed lug, one end of the lug being beveled downwardly and centrally, a bolt 25 passing through the cap opposite said beveled end, and a nut engaging the screw-threads of the bolt and engageable with the beveled face of the lug, the opposite end of the lug adjacent the inner face of the cap being formed with a notch.
3. The combination with a body having 30 an upstanding wall, of a cap for closing pas-

sage through the body and having a lug extending downward into the body, one end of the lug being adapted to fit against the inside face of the body, the opposite end of the lug being beveled upward and outward, 40 a bolt loosely disposed through the cap and having a many-sided head whereby it may be rotated, and a nut engaging the screw-threads of the bolt, the nut bearing against the inside face of the body and against the 45 beveled face of the lug when the nut is turned upward on the bolt.

4. The combination with a body having an upstanding wall, of a cap having a projecting lug and means mounted on the cap 50 adapted to be shifted into wedging engagement between the wall and the lug to prevent the removal of the cap.

5. The combination with a body having an upstanding wall, of a cap for closing the body, and means for locking the cap to the body comprising a lug depending from the body having an upwardly and outwardly beveled face, a nut engageable between the beveled face of the lug and the wall of the body, and means on the cap whereby the nut may be forced into said wedging engagement to thereby lock the cap to the body.

In testimony whereof I hereunto affix my signature in the presence of two witnesses.

CLEMENT V. WHALLON.
